UNITED STATES PATENT OFFICE.

DORA HARRISON, OF LANSING, MICHIGAN.

DESIGN FOR A BUCKLE.

SPECIFICATION forming part of Design No. 22,111, dated January 10, 1893.

Application filed December 2, 1892. Serial No. 453,888. Term of patent 14 years.

To all whom it may concern:

Be it known that I, DORA HARRISON, of Lansing, in the county of Ingham and State of Michigan, have invented and produced a 5 new and original Design for a Buckle, of which the following is a specification.

Reference is to be had to the accompanying drawing forming a part of this specification, in which my newly designed buckle is shown 10 in perspective.

The leading feature of my design consists of a loop-like figure A, approximately rectangular in shape, with one end partly open, and parallel shanks B extending from the 15 terminal points a of this end, at right angles thereto. The outer ends of the shanks B are pointed and a band-like figure C connects the two shanks with each other. From the terminal points a of the loop extends an approxi-

mately U-shaped frame D, the parallel sides 20 E of which are arranged outside the shanks B, and the ends of the said sides E are formed with band or eye-like figures E' surrounding the terminal points a. The sides E are bulged outward at F, near the middle flattened part 25 G of the frame D, and this flattened part is ornamented on top with recesses H, in alignment with the points of the shanks B. The closed buckle viewed from the front end presents a concaved or curved appearance the 30 curvature extending lengthwise of the buckle.

I claim—

The design for a buckle as herein shown and described.

DORA HARRISON.
